US0D1084594S

(12) **United States Design Patent** (10) **Patent No.:** **US D1,084,594 S**
(45) **Date of Patent:** **** Jul. 22, 2025**

(54) **GARMENT**

- (71) Applicant: **LULULEMON ATHLETICA CANADA INC.**, Vancouver (CA)
- (72) Inventor: **Kim Bernice Wormgoor**, Vancouver (CA)
- (73) Assignee: **LULULEMON ATHLETICA CANADA INC.**, Vancouver (CA)
- (**) Term: **15 Years**
- (21) Appl. No.: **29/849,122**
- (22) Filed: **Aug. 8, 2022**

Related U.S. Application Data

- (62) Division of application No. 29/746,025, filed on Aug. 11, 2020, now Pat. No. Des. 963,289.

(57) **CLAIM**

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a front view of the garment shown in an environment of use; and, FIG. 8 is a rear view of the garment shown in an environment of use.

The portions of the garment shown in broken lines in FIGS. 1-8 do not form part of the claimed design. The broken line showing of the arms, torso, neck, and head in FIGS. 7-8 is for the purpose of illustrating portions of the environmental structure and forms no part of the claimed design.

1 Claim, 8 Drawing Sheets
